UNITED STATES PATENT OFFICE.

JAMES M. KELLER, OF LOS ANGELES, CALIFORNIA.

FEED-WATER HEATER.

SPECIFICATION forming part of Letters Patent No. 783,439, dated February 28, 1905.

Application filed March 2, 1904. Serial No. 196,238.

To all whom it may concern:

Be it known that I, JAMES M. KELLER, a citizen of the United States, residing at Los Angeles, county of Los Angeles, State of California, have invented and discovered a new and useful Improvement in a Combined Feed-Water Heater and Condenser; and I do hereby declare the following to be a full, clear, and exact description of the invention, such as will enable others skilled in the art to which it appertains to make and use the same.

This invention relates to improvements in combined feed-water heaters and condensers; and the objects of my improvement are, first, to provide an apparatus for facilitating and economizing the condensation of feed-water for boilers; second, to purify feed-water to be supplied to boilers of engines, and, third, to reduce the cost and expense of operating boilers for engines, reference being made to the accompanying drawings, and to the reference-numerals marked thereon.

The invention consists, essentially, in the construction, combination, and arrangement of the several parts, as will hereinafter be fully described in the specification, shown upon the drawings appended hereto, and specifically pointed out in the claims made a part hereof.

I attain these objects by the construction and arrangement of the parts of the apparatus illustrated upon the accompanying drawings, in which—

Figure 1 is a view in perspective of my improved apparatus, portions of the casing and other parts thereof broken away; and Fig. 2 is a perspective view of one of the horizontal partition-plates removed from the apparatus, showing a deflecting-plate and an end flange secured thereto.

Similar reference - numerals refer to like parts throughout the several views.

The reference-numeral 1 denotes the casing inclosing the parts comprising the apparatus.

2, 3, 4, and 5 represent the horizontal partition-plates of the apparatus, which extend from the front side portion 1' to the rear side portion 1" thereof, forming compartments 2', 3', 4', 5', and 6", which are separated from each

other, except for the passage-ways 2", 3", 4", 5" and 5", the said passage-ways forming the only means of communication for the steam and vapor to pass downward from one of the said compartments to the other. These partition-plates 2, 3, 4, and 5 are identical in construction, except the deflecting-plate attached to the said horizontal partition-plate 4, which is perforated to permit the oil-pipes 30 and 31, hereinafter referred to, to pass through the same, and the description of one of the said deflecting-plates will serve for all. The said horizontal partition-plates are secured to the front portion 1' and to the rear portion 1" of the casing 1 by means of bolts or rivets 77, which pass through perforations 7' 7" in the vertical flanges 7" 7" and through the edges of the said deflecting-plates. The flanges 7" 7" are preferably made a part of the horizontal partition-plates and of the deflecting-plates. To the end of each of said partition-plates opposite to that which 70 abuts against the inner faces of the ends 6 6' of the casing 1 I secure to the upper face thereof the cross-flange 8 by means of bolts or rivets 8', and to the under face of each of the said horizontal partition-plates I fasten 75 the deflecting-plate 9, (shown in full and dotted lines upon Fig. 2 of the drawings,) provided with perforations 7' 7", through which the bolts or rivets 7 7 after being passed through the front side portion 1' and the rear 80 side portion 1" of the casing 1 securely hold the said deflecting-plate 9 in position. These deflecting-plates serve to direct the steam and vapor passing under the said horizontal partition-plate to which it is attached downward 85 upon the adjacent partition-plate immediately below, and the cross-flanges 8 8 retard the steam passing over the said horizontal partition-plates, causing the steam to be deflected upward again against the horizontal plate immediately above that to which the said flanges 8 8 are secured, thereby aiding the condensation 90 of the steam in passing through the apparatus.

To the lowermost partition-plate 5, on the under side thereof depending vertically downward therefrom, I secure in any suitable manner the downwardly-projecting trap-plates 12

12, extending from the front portion 1' of the casing 1 to the opposite rear portion 1", which downwardly-projecting cross-plates 12 12 extend near to the bottom of the compartment 5 6" of the casing 1. Projecting upwardly from the bottom of the compartment 6" of the casing 1 and secured thereto are the upwardly-projecting trap-plates 13 13, which, like the trap-plates 12, extend from the front portion 10 1' to the opposite rear portion 1" of the casing 1. The said trap-plates 12 12 and 13 13 in the compartment 6" of the casing 1 form traps by means of which the oil taken up by the steam used for lubricating portions of the 15 piston, piston-head, and other parts of the engine found commingled with the water condensed from the steam in the compartment 6" is drawn off through the overflow-pipe 15 from the surface of the water in the said compartment 6".

All the compartments 2', 3', 4', 5', and 6" are cleaned out by opening the valve 17 in the blow-out pipe 16 and permitting the steam admitted through the pipe 18 from the 25 exhaust of the main engine (not necessary to be shown) and the steam through the pipe 19, leading from the exhaust of the pump 20 into the uppermost compartment 2', to be forced through the casing 1 of the apparatus, there- 30 by removing therefrom all fluid foreign objectionable matter therein. Any solid matter not carried off from the said compartments of the casing 1 by forcing steam therethrough is readily removed through the hand-holes 21 35 21, which afford easy access to each of the said compartments of the casing, which hand-holes are provided with means for securely closing the same after the said solid matter is removed.

40 By means of the pipe 25 the water condensed from the steam in the compartment 6" of the casing 1, from which the oil hereinbefore referred to has been drawn off from the surface thereof through the overflow-pipe 15, is drawn 45 from the traps formed by the said trap-plates 12 12 and 13 13 in the compartment 6". The said water condensed from the steam is drawn out and forced through the pipe 26, a portion of which is coiled in the uppermost compart- 50 ment 2' of the casing, around which the steam hereinbefore mentioned admitted into said compartment circulates, and is again carried by the pipe 27 from the casing 1 to the boiler of the engine (not shown) for operating the 55 plant.

Extending from end to end of the casing 1 through the deflecting-plate 9 within the compartment 4' thereof are the inlet and outlet pipes 30 and 31, respectively. By means of 60 the former oil from a suitable receptacle (not necessary to be shown) is conveyed therefrom through the casing 1 and there heated, and from the said casing the oil is carried to the fire-box under the boiler (not shown) of the

main engine for operating the plant of which 65 the said apparatus is a part. This arrangement for heating the oil supplying fuel for operating the entire plant is an economical one and is entitled to great consideration in operating large plants where large quantities 70 of fuel are consumed.

The spray-pipe 35, perforated and within the compartment 3' of the casing, is connected with the water-supply system in the street where the plant of which the said casing is a 75 part is located. The said spray-pipe is designed to convey water to the casing 1 whenever there is a deficiency of the same therein.

The numeral 37 refers to the vent of the apparatus for the escape of steam when the 80 quantity and pressure of the same has become too great.

It is obvious that many variations and changes in the details of construction and arrangement of my invention would readily suggest themselves to persons skilled in the art to which it appertains and still be within the spirit and scope of my invention.

I do not desire to confine this invention to the specific construction, combination, and arrangement of parts herein shown and described, and the right is reserved to make all changes in and modifications of the same as come within the spirit of this invention; but I do desire to secure as my invention all features 95 of construction and equivalents thereof that come within the scope of my improvement, as herein shown and described, and illustrated upon the drawings appended hereto.

What I do claim as my invention, and desire to secure by Letters Patent, is—

1. A combined feed-water heating and condensing apparatus comprising a casing having compartments therein, partition-plates abutted at one end against one end of the casing 105 and the opposite ends of said plates free leaving a passage-way between the free ends thereof and the opposite end of the casing, a deflecting-plate secured to the under side near the abutted end thereof, a flange fastened to 110 the upper face of said partition-plates at the free end thereof, coiled pipes in the uppermost compartment of said casing, pipes connecting the lowermost compartment of the said casing with the coiled pipes in the said 115 uppermost compartment of the casing and means for forcing the water through said pipes.

2. A combined feed-water heating and condensing apparatus comprising a casing having 120 compartments therein, partition-plates secured within the apparatus, the apparatus provided with passage-ways at the end of said plates, deflecting-plates secured to the under side of said partition-plates at an angle thereto, flanges fastened to the end of said partition-plates, coiled pipes in the uppermost compartment of the apparatus, traps in the low-

est compartment of said apparatus, and means for conveying water condensed from the steam and forcing the same from the said lowermost compartment through the said coiled pipes.

3. A combined feed-water-heating apparatus, comprising a casing, partition-plates within the casing forming compartments therein, the apparatus provided with passage-ways between the ends of the partition-plates and the ends of the casing, deflecting-plates secured at an angle to the under side of the partition-plates, flanges fastened to the upper side of said partition-plates, the traps within the

lower compartment of the casing, the coiled pipes in the upper compartment of the casing, the casing provided with inlet-pipes for exhaust-steam, pipes for conveying water condensed from the steam from the said lower compartment to and through the coiled pipes in the upper compartment of the casing.

In testimony whereof I have signed my name to this specification in the presence of two subscribing witnesses.

JAMES M. KELLER.
